UNITED STATES PATENT OFFICE.

HENRY GINTZ, OF AKRON, OHIO.

BUNG-HOLE PROTECTOR.

SPECIFICATION forming part of Letters Patent No. 270,050, dated January 2, 1883.

Application filed October 21, 1882. (No model.)

To all whom it may concern:

Be it known that I, HENRY GINTZ, of Akron, in the county of Summit and State of Ohio, have invented certain new and useful Improvements in Bung-Hole Protectors; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of part of a cask or barrel provided with my bung-protector. Fig. 2 is a plan view of the under side of the device detached, and Fig. 3 is a longitudinal sectional view of the same.

Similar letters of reference indicate corresponding parts in all the figures.

My invention has relation to devices for protecting bungs of casks or barrels and for closing the bung-holes after the bung has been removed; and it consists in the improved construction of parts of such a device, which will be hereinafter more fully described.

In the accompanying drawings, the letter A represents the head of a cask or barrel, and B the staves.

C is a plate or block of metal, the outside of which fits into the curve or chine of the staves, to the upper part of which it is fastened, immediately above the head, by means of screw-bolts or other suitable means. A lip, D, projects from the inner side of the plate C, nearly 35 touching the head of the barrel when it is in position.

On a stud, E, which may be screwed or riveted into the lip D, is pivoted a spring-steel arm, F, which presses hard against the head 40 of the cask or barrel. The stud E may be fastened to the under side of the lip D either by being screwed in, driven through a hole in the lip, and swaged on the other side, or by being made in one piece with the lip and passing through a hole in the one end of the arm 45 F, swaged over it to hold it fast, which latter way I prefer, and have shown in Fig. 3 of the drawings. The outer free end of the arm F forms a disk, G, to the under side of which a 50 disk, H, of leather, rubber, or any other yielding material, is fastened.

As the simplest and most effectual stopper, I prefer to use a round disk of leather or rubber, and fasten it by driving a rivet, I, through the rubber disk H and the end G of the arm, 55 and swaging the end of it on the upper side of the arm. The disk may, however, be made in a more elaborate manner, in the same shape as the rubber to certain bottle-stoppers, adapted to be buttoned over a button fastened to 60 the under side of disk G, or in any other desirable manner.

The under side of the lip D, facing the head of the cask, has two recesses, J J, one on each side, to receive the two bent ends of a steel-wire clamp, K. This clamp consists of a piece of steel wire bent in the middle, its two arms running parallel, and having their outer ends bent inwardly at right angles with the arms. The plate C is fastened to the inside of the 70 chine in such a position that in turning the arm F on the stud E it will cover the bung or bung-hole with the disks G and H. When the bung has been removed and the contents of the cask have been drawn off, the arm is 75 turned till the disks cover the bung-hole, the yielding lower disk entering partly in the hole and closing it tightly, thus excluding dirt or small animals which might enter the cask.

For the purpose of moving the arm easier 80 and raising it slightly from the head of the cask, on which it bears heavily by the strength of the spring-steel, the clamp is removed from the recesses in the under side of the lip and the bent ends introduced on both sides under 85 the arm, when a better hold is afforded for moving it. When the arm is in position the bent ends of the clamp are again slipped into the recesses in the lip, and form a hold or handle for the easier handling of the cask, for 90 which purpose the central portion of it may be covered with leather, wood, or other material. The disks may also be placed over the bung to protect it and to hold a revenue-stamp, where such are used, or any label that may be desired to place over the bung.

Having thus described my invention, I claim and desire to secure by Letters Patent of the United States—

The device for protecting bungs and bung-holes, consisting of a curved plate adapted to be secured to the staves of a cask, and pro-

vided with a projecting lip recessed at both sides of its under side, a spring-steel arm pivoted to the said lip and provided at its outer disk-shaped end with a disk of yielding material adapted to cover the bung or bung-hole of a cask, and a steel-wire clamp having parallel arms bent inwardly at right angles at their outer ends, and said ends fitting into the cylindrical recesses in the under side of the

lip, substantially as and for the purpose here-
in shown and described.

In testimony that I claim the foregoing as my own I have hereunto affixed my signature in presence of two witnesses.

HENRY GINTZ.
